UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

ADDRESSING-MACHINE.

1,110,118.

Specification of Letters Patent. Patented Sept. 8, 1914.

Original application filed April 5, 1912, Serial No. 688,635. Divided and this application filed July 22, 1912. Serial No. 711,112.

To all whom it may concern:

Be it known that I, JOSEPH S. DUNCAN, a citizen of the United States, residing at Chicago, in the county of Cook and State of Illinois, have invented certain new and useful Improvements in Addressing-Machines, of which the following is a specification.

This invention relates to machines for printing addresses or other subject matter on envelopes and the like and constitutes a division of my prior application, Serial No. 688,635, filed April 5, 1912, now Patent No. 1,080,202 dated Dec. 2, 1913.

One of the objects of the invention is the provision of a bed or member for supporting the printing device during the printing operation in a substantial and rigid manner to insure the maintenance of the printing characters in a common plane, so that uniform and homogeneous impressions may be produced therefrom.

Another object of the invention is to so mount the supporting bed that it will be normally disposed beneath the path of travel of the printing devices as they are moved consecutively to printing position from a supply and to provide mechanism for raising the bed into engagement with each printing device disposed thereover so that the device will be supported and reinforced by the bed during the printing operation.

Other objects and advantages of the present invention will be apparent from the following description when considered in connection with the accompanying drawings illustrating one preferred embodiment thereof.

Referring to the drawings—Figure 1 is a fragmentary longitudinal sectional view of an addressing machine showing so much thereof as is necessary to an understanding of the present invention; Fig. 2 is an enlarged sectional view through a printing device, the bed and the operating slide; and Fig. 3 is a sectional view on the line 3-3 of Fig. 2.

On the drawings, 4 designates the main frame of the machine upon which the various mechanisms are mounted. The printing devices, which preferably consist each of a metallic plate 5 provided with longitudinally disposed open-ended slots 6 in which are positioned the individual type 7 arranged to produce the desired printed ad-

resses, are fed from a common supply, preferably a magazine (not shown) located at the rear of the machine, to printing position by a chain carrier 8, or other suitable mechanism. One of the sprocket wheels around which this carrier travels is indicated at 9 and is mounted upon a shaft 11 in the main frame 4. An envelop plate 12, upon which the envelopes or other matter to be printed are supported, is disposed above the printing device when in printing position and is provided with an opening 13 through which the impressions are produced on the envelopes. A suitable platen 14 adapted to co-operate with the printing devices is mounted in a frame 15. Any suitable mechanism may be employed for operating the envelop plate and the platen, one practical construction being fully disclosed in the afore-mentioned application of which the present application constitutes a division.

The envelopes or other matter to be printed are fed by hand or suitable mechanism into printing position above the opening 13 in the envelop plate and the printing devices are fed consecutively to printing position beneath this opening by a chain carrier or other suitable mechanism, as previously stated. In order that uniform and homogeneous impressions may be made from the individual types of the printing devices, I have provided a bed 16 which is secured upon a yoke 17, the rearwardly extending arms of which are pivotally mounted upon the main frame of the machine at 18. Normally the bed 16 is disposed beneath the plane of the travel of the printing devices so as not to interfere with their movement. At the proper time, however, and after a printing device has been stopped in printing position beneath the opening 13, the bed is elevated to contact with the bottom of the device and rigidly support the same during the printing operation. The bed as shown is formed on its under side to provide a plurality of inclined or cam surfaces 19. Beneath the bed there is disposed a slide 21 having similarly inclined surfaces 22 adapted upon longitudinal movement thereof to engage with the cam surfaces 19 and elevate the bed. The slide 21 extends rearwardly of the machine and is pivotally connected at its rear end at 23 with an arm 24 secured upon

a rock shaft 25 mounted in the machine frame and adapted to be rocked at requisite intervals by suitable mechanism timed to operate synchronously with the platen. 5 Upon operation of the mechanism the shaft 25 is rocked in a counter-clockwise direction, viewing Fig. 1, with the result that the slide 21 is moved forward to raise the bed 16 into engagement with the underside of 10 the printing device. Upon return of the slide to normal position the bed is retracted or redrawn from the printing position by a tension spring 26 secured at one end to a pin 27 projecting from the end of the yoke 15 17 and at its other end to the shaft 11, or any other fixed point.

I have found that the best results are obtained when the printing device is supported between the lines of printing characters 20 rather than beneath the characters themselves and I have, therefore, provided the bed 16 with upwardly extended ribs or projections 28 tapered at their upper edges to facilitate their entrance between the lower 25 ends of the type and adapted, when the bed is raised, to engage the printing device between the lines of characters and rigidly support the same during the printing operation. It will be observed that the bases of 30 the printing characters 7 are also tapered beneath the plate to permit the ribs or projections 28 to enter readily therebetween and contact with the plate between the type-receiving slots. A rigid and substantial support is, therefore, afforded for the printing 35 device during the printing operation and, after the printing operation has been completed, the support is retracted or withdrawn to permit the printing device to pass 40 on to the delivery end of the carrier and a succeeding device to be carried into printing position. An inking ribbon (not shown) is preferably mounted to travel between the printing devices and the platen and, in the 45 present instance, I have provided suitable guideways 29 on the bottom of the envelop plate 12 in which the ribbon may be guided, if desired.

It is believed that my invention will be 50 understood from the foregoing without further description and, it will be under-

stood, that the details of construction shown and described are capable of considerable modification without departure from the spirit of the invention or the scope of the 55 appended claims.

I claim:

1. In an addressing machine, the combination of a plate carrying addresses composed of lines of type supported by the plate to extend both above and beneath the plate, a movable bed provided with parallel ribs to support the plate between the lines of type, said bed ribs and the portion of the type extending beneath the plate being tapered 60 in a direction parallel with the lines of type to facilitate the entrance of the bed ribs between the lines, and means including a pivoted yoke provided with inclined faces and means cooperating therewith for elevating 65 said bed into engagement with the plate.

2. In an addressing machine, the combination of a plate provided with parallel slots, type disposed in said slots and projecting above and beneath the plate, a movable bed 70 provided with parallel ribs adapted to support the plate between the rows of type, said type being tapered, parallel with the lines of type beneath the plate and said bed ribs being also tapered to facilitate the entrance of 75 the bed ribs between the lines, and means including a plurality of pairs of cooperating inclined relatively movable faces for elevating the bed at predetermined intervals to bring the ribs into engagement with the 80 plate between the rows of type.

3. In an addressing machine, the combination of a bed provided with ribs adapted to form a support for a printing device between the lines of type thereof, a pivoted 90 yoke upon which said bed is mounted, provided with a plurality of parallelly inclined faces on its lower side, a reciprocatory slide arranged beneath said bed and provided with correspondingly inclined faces adapted 95 to engage said inclined faces of the bed, and means for actuating said slide to raise and lower said bed.

JOSEPH S. DUNCAN.
